(57) **CLAIM**

The ornamental design for a battery pack, as shown and described.

DESCRIPTION

FIG. 1 is a perspective front view of the battery pack;
FIG. 2 is a front view of the battery pack;
FIG. 3 is a rear view of the battery pack;
FIG. 4 is a left-hand-side view of the battery pack;
FIG. 5 is a right-hand-side view of the battery pack;
FIG. 6 is a top view of the battery pack;
FIG. 7 is a bottom view of the battery pack;
FIG. 8 is a perspective front view of an alternative embodiment of the battery pack;
FIG. 9 is a front view of the alternative embodiment of FIG. 8 of the battery pack;
FIG. 10 is a rear view of the alternative embodiment of FIG. 8 of the battery pack;
FIG. 11 is a left-hand-side view of the alternative embodiment of FIG. 8 of the battery pack;
FIG. 12 is a right-hand-side view of the alternative embodiment of FIG. 8 of the battery pack;
FIG. 13 is a top view of the alternative embodiment of FIG. 8 of the battery pack;
FIG. 14 is a bottom view of the alternative embodiment of FIG. 8 of the battery pack;
FIG. 15 is a perspective front view of another alternative embodiment of the battery pack;
FIG. 16 is a front view of the alternative embodiment of FIG. 15 of the battery pack;
FIG. 17 is a rear view of the alternative embodiment of FIG. 15 of the battery pack;
FIG. 18 is a left-hand-side view of the alternative embodiment of FIG. 15 of the battery pack;
FIG. 19 is a right-hand-side view of the alternative embodiment of FIG. 15 of the battery pack;
FIG. 20 is a top view of the alternative embodiment of FIG. 15 of the battery pack; and,
FIG. 21 is a bottom view of the alternative embodiment of FIG. 15 of the battery pack.
